(57) **CLAIM**

The ornamental design for a brain sensing headband, as shown and described.

DESCRIPTION

FIG. 1 is a front perspective view of the brain sensing headband, as it could appear when worn.

FIG. 2 is a front perspective view of the brain sensing headband.

FIG. 3 is a rear perspective view of the brain sensing headband.

FIG. 4 is a right side elevation view of the brain sensing headband.

FIG. 5 is a front elevation view of the brain sensing headband.

FIG. 6 is a left side elevation view of the brain sensing headband.

FIG. 7 is a rear elevation view of the brain sensing headband.

FIG. 8 is a top plan view of the brain sensing headband; and, FIG. 9 is a bottom plan view of the brain sensing headband. The partial human figure shown in stippled lines in FIG. 1 is environmental subject matter that forms no part of the claimed design.
